TOY ROBOT

Laurie J. Campbell, Erie, Pa., assignor to Louis Marx & Co., Inc., New York, N.Y., a corporation of New York

Filed July 11, 1963, Ser. No. 75,750

Term of patent 14 years

(Cl. D34—15)

FIG. 1.

FIG. 2.

FIG. 5.

FIG. 4.

FIG. 1 is a front view of a toy robot showing my new design;

FIG. 2 is a rear view thereof;

FIG. 3 is a side view thereof;

FIG. 4 is a view similar to FIG. 3, showing the opposite side thereof;

FIG. 5 is a top view thereof.

I claim:

The ornamental design for a toy robot, as shown.
